US00D949718S

(12) **United States Design Patent** (10) **Patent No.:** **US D949,718 S**
Arbuckle et al. (45) **Date of Patent:** **** Apr. 26, 2022**

(54) **WALL PUNCH**

(71) Applicants: **William Arbuckle**, Paso Robles, CA (US); **Michael Van Horst**, Fresno, CA (US)

(72) Inventors: **William Arbuckle**, Paso Robles, CA (US); **Michael Van Horst**, Fresno, CA (US)

(**) Term: **15 Years**

(21) Appl. No.: **29/679,772**

(22) Filed: **Feb. 8, 2019**

Related U.S. Application Data

(63) Continuation-in-part of application No. 15/390,312, filed on Dec. 23, 2016, now Pat. No. 10,328,557, which is a continuation-in-part of application No. 29/584,846, filed on Nov. 17, 2016, now Pat. No. Des. 819,465.
